UNITED STATES PATENT OFFICE.

EDMUND C. WESTERVELT AND CHARLES W. CLAPP, OF SOUTH BEND,
INDIANA.

RIDING DISK PLOW.

SPECIFICATION forming part of Letters Patent No. 662,845, dated November 27, 1900.

Application filed March 17, 1900. Serial No. 9,106. (No model.)

To all whom it may concern:

Be it known that we, EDMUND C. WESTERVELT and CHARLES W. CLAPP, of South Bend, St. Joseph county, Indiana, have invented 5 certain new and useful Improvements in Riding Disk Plows; and we hereby declare that the following is a full, clear, and exact description thereof, reference being had to the accompanying drawings, which form part of 10 this specification.

This invention is an improvement in riding disk plows, and has particular reference to (a) the mounting of the front staggered wheel and the means for adjusting the same, (b) the 15 means for attaching the draft or double tree to the frame, (c) the novel construction and arrangement of the scrapers for the disk plows, and (d) novel means for alining and locking the rear guide-wheels of the plows. 20 These are the principal objects of the improvement; but other features and the advantages of the invention will be set forth in the detailed description following.

The invention therefore consists in the 25 novel construction, combinations, and sub-combinations of parts summarized in the claims appended to the following description of the plow illustrated in the accompanying drawings, in which—

30 Figure 1 is a perspective view of the complete plow. Fig. 2 is a plan view. Fig. 3 is a side elevation. Fig. 4 is a front elevation.

The plow consists, essentially, of a frame A of approximately triangular shape in plan, to 35 the base of which triangle forming the front of the machine are attached the draft devices. To the inclined furrow side of the frame are attached the cutting-disks, of which one or more may be used. In the drawings I have 40 shown only one disk; but when more are employed they will simply be attached to the furrow side of the frame, one in advance of the other, as in the usual arrangement of gang-plows. To the land side of the frame is 45 attached a land-wheel B, mounted on a cranked axle B', which is adjusted by a hand-lever B² and segment B³, as usual. To the front furrow side corner of the frame is attached a casting C, which may be flanged 50 over the front bar of the frame and is secured by bolts c, which pass through slots c' in the

casting, so that the casting can be adjusted laterally upon the frame, if desired, to accommodate the wheel to the width of the furrow that is being cut. This casting is provided with forwardly-projecting lugs c², to which the clevis H or draft-trees may be attached. It is also provided with upper and lower pairs of eyes c³ and c⁴, in which are journaled short horizontal crank-shafts D D, 55 the outer crank ends of which are journaled in bearings in a sleeve E, in which is journaled a shaft F, the lower end of which is inclined at an angle of about forty-five degrees and carries a staggered furrow or guide wheel 60 e. The upper end of the shaft F is bent inwardly over the frame, as shown at F', and to it is connected the tongue f, so that the wheel e is controlled by the movement of the tongue, and thus the plow is guided independently of the draft thereon. By reason 65 of the double cranks D D the wheel e can be vertically raised and lowered without changing its inclination in the furrow by means of a crank d, attached to the upper shaft D and 70 connected by a rod d' to a lever d², pivoted on the frame and provided with a hand-latch, as usual, adapted to engage a segment d³ on the frame, as shown.

Attached to the front bar of the frame beside casting C is another casting G, which is provided with forwardly-projecting lugs g², similar to the lugs c² on casting C, and, like the latter, adapted for the attachment of a clevis H. The draft-block G is also preferably flanged over the front bar of the frame and is secured thereto by means of bolts G', which may engage slots in the frame or in the casting G, so as to permit the lateral adjustment of the latter on the frame. The 80 castings C and G thus permit of a range of adjustment of the point of attachment of the clevis to the frame as will best suit the varying conditions of the work to be done and the number of horses to be employed. 85

The rear end of the frame A is supported by a caster-wheel I, mounted on a crank-axle I', swiveled in the casting J, attached to the frame. Pivoted to the casting J beside the shaft I' is a lever K, the lower end of which 90 when the lever is in one position limits the motion of wheel I in one direction, but leav- 95

ing it free to move away from it in the opposite direction. The wheel I follows in the furrow which has been formed by the disk immediately preceding it. When lever K is thrown backward, the wheel I becomes a free caster-wheel and can turn to the right or left. The lever K is thrown backward when the plow is turned to the right, and when it is again straightened in the furrow lever K is thrown forward and its lower end *k* strikes against the horizontal portion of the crank-axle I' and forces wheel I back into proper position. This is practically quite important, for if the caster-wheel is left to swing freely it will not remain properly in place and will cause an irregular movement or cut of the plow. Further, by means of this lever the correct alinement of the wheel is obtained and insured while the plow is proceeding with its work, and the necessity of partially pulling the plow out of its course, as is necessary when a latch or lock is used, in order to get the wheel in alinement is avoided. A strap *k*² may be attached to casting J below the pivot of lever K to relieve the latter of the lateral thrust on the end of said lever.

The lower front portion of casting J is provided with a bearing *j* for the shaft *l* of the disk L, which is of ordinary construction. The disk is provided with a scraper M, which, because of its peculiar construction and adjustment, acts as a moldboard and will turn the furrow entirely over, as in an ordinary moldboard-plow. This scraper, as shown, is made to cover a little more than one-half of the disk and is located in rear of and extends slightly above the hub of the disk, being adjustably connected to the rod *m*, which is in turn fastened to a bracket *m'* on or secured to casting J. Just in rear of the disk L is attached a horizontally-disposed cutter O, preferably a rotary one, mounted upon a shaft O', which is journaled in a vertical sleeve P, attached to or formed on the casting J in rear of the disk. This cutter O operates at the bottom of the furrow to loosen the ground for the succeeding furrow, so that the latter can be easily turned over as a whole when the plow comes by the second time. The form of frame shown does away with the necessity for a plow-beam, and by reason of the ample adjustments provided for the clevis attachment the draft can be so equally balanced that the machine will be practically self-guiding. At least it can be very easily guided by means of the tongue, which has nothing to control except the furrow or guide wheel e, and only a very small amount of force is necessary to control its direction when at work.

Having thus described our invention, what we therefore claim as new, and desire to secure by Letters Patent thereon, is—

1. In a wheeled plow, the combination of a frame, the laterally-adjustable casting attached to the front side of the frame, the crank-shafts journaled in said casting, and the sleeve supported by said crank-shafts;

65

with the furrow-wheel shaft journaled in said sleeve having a furrow-wheel on its lower end and its upper end cranked for the attachment of the tongue, substantially as described.

2. In a wheeled plow, the combination of a frame, the laterally-adjustable casting attached thereto, the upper and lower crank-shafts attached to said casting, the sleeve suspended on said crank-shafts, and the furrow-wheel shaft journaled in said sleeve having an inclined staggered furrow-wheel on its lower end and its upper end cranked for the attachment of the tongue.

3. In a wheeled plow, the combination of the frame, the casting attached to the front end thereof provided with lugs for the attachment of a clevis and with upper and lower eyes, the crank-shafts journaled in said eyes, and the furrow-wheel supported by said shafts.

4. In a wheeled plow, the combination of the frame, the laterally-adjustable casting attached to the front end thereof provided with lugs for the attachment of a clevis and with upper and lower eyes, the crank-shafts journaled in said eyes, the sleeve suspended from said crank-shafts, the furrow-wheel shaft journaled in said sleeve, and means for adjusting the sleeve.

5. In a wheeled plow, the combination of the frame, the casting attached to the front end thereof and provided with upper and lower eyes, the upper and lower crank-shafts journaled in said eyes, the vertical sleeve supported by said crank-shafts, the furrow-wheel shaft journaled in said sleeve having a furrow-wheel on its lower end and its upper end cranked for the attachment of a tongue, and the means for rocking said crank-shafts to adjust the furrow-wheel vertically.

6. The combination of the frame, the laterally-adjustable casting attached to the front end thereof, the upper and lower crank-shafts journaled on said casting, the vertical sleeve supported by said crank-shafts, the furrow-wheel shaft journaled in said sleeve having a furrow-wheel on its lower end and its upper end cranked for the attachment of a tongue, and the crank-arm, rod, lever and segment for rocking and locking said crank-shafts to adjust the furrow-wheel vertically.

7. In a riding-plow, the combination of a pair of laterally and independently adjustable castings attached to the front bar of the frame and respectively provided with means for the attachment of a clevis or tree, substantially as and for the purpose described.

8. In a riding-plow, the combination of a pair of laterally and independently adjustable castings attached to the front bar of the frame and respectively provided with means for the attachment of a clevis; with the furrow-wheel, the supports therefor attached to and supported by one of said castings, and means for vertically adjusting said furrow-wheel.

9. In a riding-plow, the combination of a pair of laterally-adjustable castings attached

to the front bar of the frame and respectively provided with means for the attachment of a clevis or tree, upper and lower crank-shafts attached to one of said castings, the furrow-
5 wheel supported by said crank-shafts, and means for vertically adjusting said furrow-wheel.

10. In a riding-plow, the combination of a pair of castings attached to the front bar of
10 the frame and respectively provided with means for the attachment of a clevis or tree, the upper and lower crank-shafts attached to one of said castings, a vertical sleeve supported by said crank-shafts, the furrow-wheel
15 shaft journaled in said sleeve carrying a furrow-wheel on its lower end, a tongue attached to the upper end of said furrow-wheel shaft, and means for vertically adjusting said furrow-wheel.
20 11. In a wheel-plow, the combination of the caster-wheel mounted on a crank-shaft adapted to swing horizontally; with a lever pivoted beside the crank-shaft and having a projecting lower end which is adapted to limit
25 the swing of the shaft when the lever is adjusted in one position and to hold the caster in alinement in the furrow when the lever is adjusted to its other position, for the purpose and substantially as described.
30 12. In a wheel-plow, the combination of the rear caster-wheel, the crank-shaft carrying the same, a lever pivoted beside the shaft and adapted to have its lower end project into the path of the shaft when the lever is adjusted
35 in one position for the purpose of forcing the caster-wheel into alinement in the furrow and retaining it in such position, for the purpose and substantially as described.

13. In a wheel-plow, the combination of the frame, the land-wheel, the casting attached to the front of the frame, the shaft supported on said casting having a furrow-wheel journaled on its lower end and its upper end bent over the frame for the attachment of the tongue; and means for adjusting the furrow-wheel vertically; with the horizontally-swinging
45 caster-wheel attached to the rear end of the frame and the pivoted lever beside the caster-wheel adapted to force it into alinement and hold it in alinement with the furrow, all substantially as described.

14. In a wheel-plow, the combination of the frame, the land-wheel, the laterally-adjustable casting attached to the front of the frame, the crank-shafts on said casting, a sleeve supported by said crank-shafts, a shaft journaled in the sleeve having a furrow-wheel journaled on its lower end, and means for adjusting the furrow-wheel vertically;
55 with the caster-wheel attached to the rear end of the frame by a horizontally-swinging crank-axle, and the lever pivoted to the frame beside the caster-wheel and adapted to force the same into alinement and hold it in alinement with the furrow, all substantially as described.

15. In a disk plow, the combination of the

frame, the land-wheel, the casting attached to the front of the frame, a shaft supported from said casting having a furrow-wheel journaled on its lower end and its upper end bent over the frame for the attachment of a tongue and means for adjusting the furrow-wheel vertically, and a plow attached to the frame in rear of the furrow-wheel, with the horizontally-swinging caster-wheel attached to the rear end of the frame, and the lever pivoted to the frame beside the caster-wheel adapted to force and hold it in alinement with the furrow, all substantially as described. 70

16. In a disk plow, the combination of the frame, the land-wheel, the laterally-adjustable casting attached to the front of the frame, the crank-shafts on said casting, a furrow-wheel supported from said crank-shafts, and means for adjusting the furrow-wheel vertically, the disk plow attached to the frame in rear of the furrow-wheel, the caster-wheel attached to the rear end of the frame, and the lever pivoted beside the caster-wheel and adapted to force and hold it in alinement with the furrow, all substantially as described. 75 80

17. In a disk plow, the combination of the frame, the land-wheel, the casting attached to the front of the frame, the crank-shafts on said casting, a sleeve supported by said crank-shafts, a shaft journaled in the sleeve having a furrow-wheel journaled on its lower end and its upper end bent over the frame for the attachment of a tongue, and means for adjusting the furrow-wheel vertically, a disk plow attached to the frame in rear of the furrow-wheel, an adjustable scraper for said disk, the caster-wheel attached to the rear end of the frame and the lever pivoted to the frame 95 beside the caster-wheel and adapted to force and hold it in alinement with the furrow, all substantially as described. 100

18. In a disk plow, the combination of the frame, the land-wheel, the laterally-adjustable casting attached to the front of the frame, the crank-shafts on said casting, a sleeve supported by said crank-shafts, a shaft journaled in the sleeve having a furrow-wheel journaled on its lower end and its upper end bent over the frame for the attachment of a tongue and means for adjusting the furrow-wheel vertically, a disk plow attached to the frame in rear of the furrow-wheel, with a horizontally-disposed cutter in the furrow behind said 110 disk, the caster-wheel attached to the rear end of the frame, and the lever pivoted to the frame beside the caster-wheel and adapted to force and hold it in alinement with the furrow, all substantially as described. 115 120 125

In testimony that we claim the foregoing as our own we affix our signatures in presence of two witnesses.

EDMUND C. WESTERVELT.
CHARLES W. CLAPP.

In presence of—

JAMES DUSHANE,
EDA E. ROSECRANS.
